United States Patent Office

Des. 188,222

Patented June 14, 1960

188,222

BOX FOR A BOTTLE OR SIMILAR ARTICLE

John B. Lang, 5036 Juanita Ave. S., Minneapolis, Minn.

Filed June 23, 1958, Ser. No. 51,492

Term of patent 3½ years

(Cl. D58—11)

The figure is a perspective view of a box for a bottle or similar article showing my new design.

The side not shown is the same as the side shown.

I claim:

The ornamental design for a box for a bottle or similar article, substantially as shown and described.
